[57] CLAIM

The ornamental design for a case for emergency apparatus or the like, as shown and described.

DESCRIPTION

FIG. 1 is a front elevational view of a case for emergency apparatus or the like showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

The broken lines shown in FIGS. 1, 2, 4, 5, and 6, represent conventional stitching.
